UNITED STATES PATENT OFFICE.

JOHN H. WALKER AND HENRY JIFKINS, OF SCRANTON, PENNSYLVANIA.

DESIGN FOR A CAMPAIGN-BADGE.

SPECIFICATION forming part of Design No. 25,986, dated September 8, 1896.

Application filed June 29, 1896. Serial No. 597,474. Term of patent 31 years.

To all whom it may concern:

Be it known that we, JOHN H. WALKER and HENRY JIFKINS, citizens of the United States, residing at Scranton, in the county of Lackawana and State of Pennsylvania, have invented and produced a new and novel Design for a Campaign Badge or Button, of which the following is a specification.

The leading feature of our design consists in a campaign-badge comprising a scalloped blossom representing a buttercup in full bloom, a stem, a number of leaves having panels thereon upon which suitable words are to be placed, and a pin for securing the badge to a coat or other garment.

In the accompanying drawings, Figure 1 represents a perspective view of a campaign-badge made in accordance with our design. Fig. 2 is a cross-section of the same.

In the said drawings, the reference-numeral

1 designates a five-leaved blossom having scalloped edges and representing a buttercup.

The numeral 2 designates a stem, to which the blossom is secured, provided with leaves 3.

The numerals 5 and 6 designate panels 25 upon which suitable words may be placed.

The numeral 4 designates a pin for securing the badge to a garment.

In carrying the invention into effect the blossom should be made of gold, or gilded to 30 represent gold, and the leaf should be of a green color.

What we claim is—

The design for a campaign-badge, substantially as shown and described.

JOHN H. WALKER.
HENRY JIFKINS.
